DIAGNOSTIC COMPOSITION FOR DETECTING GLUCOSE

Otis E. Fancher and Dale A. Stauffer, Elkhart, Ind., assignors to Miles Laboratories, Inc., Elkhart, Ind., a corporation of Indiana
No Drawing. Filed Nov. 6, 1959, Ser. No. 851,241
11 Claims. (Cl. 195—103.5)

This invention relates to a new and improved diagnostic composition and is particularly concerned with a diagnostic test which is useful for the qualitative detection and quantitative determination of glucose in biological fluids, such as urine, and wherein the reagent composition is incorporated upon a bibulous carrier.

The detection of glucose in urine as well as the determination of its concentration therein is of great importance for diabetic patients who must control their diets so as to regulate their sugar intake and who must frequently be guided in this regard by a regular check on urine glucose. But beyond its usefulness in regular urine testing on known diabetics by both patients and physicians, this glucose indicator may also be used efficiently in routine urinalyses in hospitals and physicians' offices, in diabetes detection screening programs, in the differentiation of glucosuria from other mellituras, and the like.

Because early diagnosis and continued control are so important in diabetes, a urine-sugar test, to be of greatest value, must be conveniently rapid, simple enough for any patient to learn with ease, accurate enough to serve the clinician, and sensitive enough to reflect variations in the patient's condition. Moreover, the reagent composition must be adequately stable.

Procedures for the detection of sugar in urine are well known in clinical chemistry. One such procedure utilizes Benedict's copper reduction test, another employs a self-heating alkaline copper reduction test in tablet form (U.S. Patent No. 2,387,244), still another involves a test which depends solely on the action of enzymes (U.S. Patent No. 2,848,308). Although these and other procedures have greatly contributed to the art of diagnosing for urine glucose, they have not entirely satisfied the above-mentioned requirement.

We have now found a novel and highly useful glucose-detecting means which represents an important improvement and a fresh approach to the problem of determining glucose in various materials including body fluids, such as urine, by a technique which utilizes a diagnostic composition that rivals even the latest and most commonly used glucose tests in stability and quantitation.

Specifically, we have now found that a certain synthetic metalloporphyrin compound is surprisingly and unexpectedly capable of acting as catalyst to induce the oxidation of indicators by hydrogen peroxide formed when glucose is aerobically oxidized in the presence of glucose oxidase. The principles underlying these reactions are well known and need not be expounded.

A diagnostic composition according to the present invention comprises as essential constituents glucose oxidase, a synthetic metalloporphyrin and a color-forming substance or indicator, such as 2,7-diaminofluorene, o-tolidine, leucomidophenols, etc.

This invention represents an improvement over previously described compositions in that the catalyst is a chemically reproducible, stable compound rather than a naturally occurring unstable enzyme mixture of a highly variable composition. Moreover, it is surprising and unexpected that very small amounts of the catalysts are sufficient to produce the desired effect. Embodiments of this invention also have advantages over the hemin-amino complexes disclosed in patent application Serial No.

2

802,281, filed March 27, 1959, by the same applicants, in that the catalyst of the present invention is water-soluble and is therefore easily applicable to carriers, such as filter paper strips, together with the glucose oxidase, the indicator, and such other ingredients as may be required to give the appropriate reaction conditions.

The metalloporphyrin used in the embodiments of this invention is a mixture of isomeric urohemin or uroferriporphyrin chlorides ($C_{40}H_{36}N_4O_{16}FeCl$), which are characterized by four acetic acid and four propionic acid groups attached to the porphyrin ring. The following structural formula characterizes one isomeric form of its complex chemical nature:

As indicated above the catalyst used in the practice of this invention is a chemically reproducible metalloporphyrin, the mode of preparation being as follows:

The porphyrins are made in accordance with the description given by MacDonald, J. Chem. Soc. (1952), 4176, 4184, and Can. J. Chem., 34, 1768 (1956). The metallation of the thus-produced porphyrins is carried out according to the general procedure of Erdman and Corwin, JACS, 69, 750 (1947). The metalloporphyrin intermediates are then hydrolysed as shown by Fischer and Orth, "Die Chemie des Pyrrols II," 1. Hälfte, p. 515. It has been suggested by MacDonald that the reaction product, as mentioned above, may be a mixture of urohemin in several isomeric forms wherein the arrangement of acetic acid and propionic acid groups varies. Separation of the isomers is not required or even desirable for the practice of this invention.

The urohemin mixture has sufficient activity to catalyze the oxidation of sensitive indicators such as 2,7-diaminofluorene without the addition of amine donors. However, amine donors, such as 2-aminobenzothiazole, nicotinic acid and pyridine make it possible to decrease the quantity of urohemin required with sensitive indicators and greatly decrease the time required for oxidation of less sensitive indicators, such as o-tolidine.

It is understood that such additives as suitable protective agents and wetting agents may be incorporated therein as illustrated below. Furthermore, this glucose test may contain a suitable inert dye to impart to the composition a uniform background color as well as an appropriate buffer system to maintain a desired pH range (pH 3 to 7 with a pH of 5.4 being preferred).

Although the test device itself may comprise the reagent composition in the form of a tablet, powder, or other embodiment, we prefer, to insure ease and simplicity of test procedure, to affix the reagent composition on bibulous base materials or carriers, such as strips or sticks of filter paper, by dissolving the component in a suitable solvent, impregnating the bibulous strips with the resulting solution and drying the impregnated test strips. As will be obvious from the examples, it is very easy to prepare the instant glucose indicator due to its manifest simplicity.

The invention will now be illustrated in greater detail, but not limited, by the following examples:

EXAMPLE I

Preparation of the Impregnating Solution

Algin (100 mg.) was stirred with 10 ml. of water until a clear solution resulted. Then 10 ml. of a pH 5.4 buffer solution (prepared by dissolving 352.8 g. of sodium citrate dihydrate and 25.6 g. of anhydrous citric acid in water and diluting to 1000 ml.) was added with stirring. A solution of 2 g. of gelatin and 150 mg. of F. D. & C. Red No. 3 (disodium salt of 9-o-carboxyphenyl-6-hydroxy-2,3,4,7-tetraiodo-3-isoxanthone) in 100 ml. of hot water was prepared and 10 ml. of this solution was added to the algin-buffer solution with stirring. Then a solution of 100 mg. of 2,7-diaminofluorene dihydrochloride in 10 ml. of hot 50% ethanol was added. A solution of 500 mg. of glucose oxidase (28,700 U./g., dialyzed and lyophilized) in 5 ml. of water was added. The mixture was warmed to 40° and a solution of 10 mg. of the synthetic urohemin in 5 ml. of water was added.

Preparation of Diagnostic Strip

A bibulous carrier, such as, filter paper cut into narrow strips with a water-impervious barrier of ethyl cellulose one-half inch from the tip were dipped into the impregnating solution so that through the process of submersion and capillary attraction the entire one-half inch of the strip up to the barrier was completely impregnated. These strips were dried in a hot air oven at 100° C. for from 30 minutes to 5 hours.

Procedure of Testing

In use an impregnated strip made as described above is dipped into the liquid specimen to be tested. When contacted with urine containing glucose, test strips gave positive reactions in about 10 seconds evidenced by various shades of blue color as follows:

With urine containing 1 or 2% glucose an intense blue color developed in 10 seconds, while with urine containing 0.1% glucose a light blue color developed in 10 seconds. With urines containing 0.25% and 0.5% glucose the blue colors which developed in 10 seconds were of intermediate intensities, the urine containing the most glucose being the darkest blue. When dipped in urine containing no glucose, the sticks underwent no color change. A simple color chart based on this phenomenon may be conveniently prepared for use in estimating the glucose content of the urine being tested.

EXAMPLE II

The impregnating solution was prepared as in Example I except that the urohemin (10 mg.) together with 20 mg. of 2-aminobenzothiazole was dissolved in 5 ml. of hot 50% aqueous ethanol and this solution was added to the rest of the mixture.

The diagnostic strips were prepared and tested as in Example I. These sticks were slightly more active than those prepared according to Example I.

EXAMPLE III

The impregnating solution was prepared as in Example I except that the 2,7-diaminofluorene dihydrochloride was replaced with o-tolidine dihydrochloride as the indicator substance and the quantity of urohemin used was doubled. The sticks were prepared and tested as in Example I. When dipped in urine containing 1% glucose, a blue color of moderate intensity developed in 1 minute. When dipped in urine containing no glucose or in urine containing 0.1% glucose, no color change was observed in 1 minute. When wet with urine containing 0.25% glucose, a faint blue color developed in 1 minute.

EXAMPLE IV

The impregnating solution was prepared by adding 200 mg. of 2-aminobenzothiazole to the solution as prepared according to Example III. The mixture was stirred and warmed to 40° to dissolve the amine. The sticks were

prepared and tested as in Example I. The test sticks had the same order of activity as those prepared according to Example I.

In summary, this invention pertains to a diagnostic composition for the detection of glucose in body fluids, and especially in urine, consisting of a bibulous strip or stick which has been impregnated with a composition comprising glucose oxidase, a metalloporphyrin, namely, an isomeric mixture of urohemin and a color-forming substance, such as, 2,7-diaminofluorene or o-tolidine which is oxidizable by hydrogen peroxide in the presence of the metalloporphyrin.

What is claimed is:

1. A diagnostic composition for detecting glucose which comprises glucose oxidase, a compound selected from the group consisting of a uroferriporphyrin chloride having the structural formula

35

2. A diagnostic composition for detecting glucose which comprises glucose oxidase, a compound selected from the group consisting of a uroferriporphyrin chloride having the structural formula

60

3. A diagnostic composition for detecting glucose which comprises glucose oxidase, a compound selected from the group consisting of a uroferriporphyrin chloride having the structural formula

groups and a color-forming substance taken from the and propionic acid groups and a color-forming substance taken from the group consisting of 2,4-diaminofluorene and o-tolidine, oxidizable by hydrogen peroxide in the presence of said uroferriporphyrin chloride.

4. A diagnostic composition for detecting glucose which comprises glucose oxidase, a compound selected from the group consisting of a uroferriporphyrin chloride having the structural formula

and compounds having the same ferriporphyrin nucleus differing therefrom only in the arrangement of acetic acid and propionic acid groups and 2,7-diaminofluorene, oxidizable by hydrogen peroxide in the presence of said uroferriporphyrin chloride.

5. A diagnostic composition for detecting glucose which comprises glucose oxidase, a compound selected from the group consisting of a uroferriporphyrin chloride having the structural formula

and compounds having the same ferriporphyrin nucleus differing therefrom only in the arrangement of acetic acid and propionic acid groups and 2,7-diaminofluorene.

6. A glucose-detecting means consisting of a bibulous carrier impregnated with a diagnostic composition comprising glucose oxidase, a compound selected from the group consisting of a uroferriporphyrin chloride having the structural formula

and compounds having the same ferriporphyrin nucleus differing therefrom only in the arrangement of acetic acid and propionic acid groups and 2,7-diaminofluorene oxidizable by hydrogen peroxide in the presence of the uroferriporphyrin chloride.

7. A diagnostic composition for detecting glucose which comprises glucose oxidase, a compound selected

from the group consisting of a uroferriporphyrin chloride having the structural formula

and compounds having the same ferriporphyrin nucleus differing therefrom only in the arrangement of acetic acid and propionic acid groups, a complex-forming compound selected from the class consisting of 2-aminobenzothiazole, nicotinic acid and pyridine to activate said uroferriporphyrin chloride and a color-forming substance oxidizable by hydrogen peroxide in the presence of the activated uroferriporphyrin chloride.

8. A diagnostic composition for detecting glucose which comprises glucose oxidase, a compound selected from the group consisting of a uroferriporphyrin chloride having the structural formula

and compounds having the same ferriporphyrin nucleus differing therefrom only in the arrangement of acetic acid and propionic acid groups, a complex-forming compound selected from the class consisting of 2-aminobenzothiazole, nicotinic acid and pyridine to activate said uroferriporphyrin chloride and a color-forming substance taken from the group consisting of 2,7-diaminofluorene and o-tolidine, oxidizable by hydrogen peroxide in the presence of the activated uroferriporphyrin chloride.

9. A diagnostic composition for detecting glucose which comprises glucose oxidase, a compound selected from the group consisting of a uroferriporphyrin chloride having the structural formula

and compounds having the same ferriporphyrin nucleus differing therefrom only in the arrangement of acetic acid and propionic acid groups, 2-aminobenzothiazole to activate said uroferriporphyrin chloride by forming a com-

plex therewith and 2,7-diaminofluorene oxidizable by hydrogen peroxide in the presence of the activated uroferrিপorphyrin chloride.

10. A diagnostic composition for detecting glucose which comprises glucose oxidase, a compound selected from the group consisting of a uroferrিপorphyrin chloride having the structural formula

and compounds having the same ferriporphyrin nucleus differing therefrom only in the arrangement of acetic acid and propionic acid groups, 2-aminobenzothiazole and 2,7-diaminofluorene.

11. A glucose-detecting means consisting of a bibulous carrier impregnated with a diagnostic composition comprising glucose oxidase, a compound selected from the

group consisting of a uroferrিপorphyrin chloride having the structural formula

15 and compounds having the same ferriporphyrin nucleus differing therefrom only in the arrangement of acetic acid and propionic acid groups, 2-aminobenzothiazole to activate said uroferrিপorphyrin chloride by forming a complex therewith, and 2,7-diaminofluorene oxidizable by hydrogen peroxide in the presence of the activated uroferrিপorphyrin chloride.
